UNITED STATES PATENT OFFICE.

WALTER HAHNEMANN, OF KITZEBERG, NEAR KIEL, GERMANY, ASSIGNOR TO THE FIRM SIGNAL GESELLSCHAFT M. B. H., OF KIEL, GERMANY.

DEVICE FOR ASSISTING NAVIGATION.

Application filed February 4, 1921. Serial No. 442,579.

To all whom it may concern:

Be it known that I, WALTER HAHNEMANN, citizen of the German Republic, and residing at Kitzeberg, near Kiel, county of Schleswig-Holstein, State of Prussia, Germany, have invented certain new and useful Improvements in and Relating to Devices for Assisting Navigation, of which the following is a specification.

- 10 The invention is concerned with a method of cable signalling in which alternating currents flow in one or more cables located on the bottom of the channel to be navigated, which currents operate by induction 15 an indicating apparatus carried on the ship. One difficulty in these methods consists in finding the beginning point of the cable upon the approach of the vessel. For this purpose auxiliary devices are 20 provided by this invention. It consists in placing a sound transmitter in the water at the end of the cable. The transmitter is preferably in the form of an electrically driven transmitter and its current supply 25 can be maintained through the cable itself. The considerably greater range of the sound signals of a powerful sound transmitter facilitates the finding of the ends of the cable and enables the vessel to be navigated 30 to the beginning of the channel indicated by the cable.

In the simplest form of my invention the same current which flows in the cable is employed for operating the sound transmitter. These currents are alternating currents and generally of a frequency which is capable of producing a suitable warning tone. They are ordinarily intermittently switched in and out by means 40 of an interrupter or key situated on land or are switched from one cable to another cable. If the sound transmitter is connected by means of a change-over switch alternately to a number of cables in rotating sequence, 45 the wave impulses which flow consecutively through the several cables to the transmitter may produce continuous tones therein which may be unsuitable for reception on account of their similarity to extraneous 50 noises arising from the water. Therefor, preferably an interrupter is suitably connected to the conductor which connects the generator with the cable. Such interrupter chops up the continuous impulses and produces in the transmitter a predetermined

sound signal, for example consisting of a series of dashes. The interrupter can be inserted between the machine and the cable as well as between the cable and transmitter. In the first case there is the advantage that 60 the interrupter can be installed on the land, but the disadvantage that the alternating currents in the cable likewise give the same signal as the sound transmitter; in the second case the difficulty must be taken into 65 consideration which arises from placing the interrupter under water.

In the accompanying drawing some examples of carrying out the invention are illustrated. 70

Fig. 1 shows an arrangement with a cable as conductor and a sound transmitter provided with an interrupter.

Fig. 2 shows an arrangement with two cables as conductor and a sound transmitter without an interrupter. 75

Fig. 3 shows a similar arrangement with an interrupter between the conductor and the machine,

Fig. 4 shows a similar arrangement with 80 the interrupter between the conductor and transmitter.

In all the figures 1 indicates an alternating current machine, which supplies the conductor consisting of the cable 2 or of 85 a plurality of cables 2 and 3.

In the example of Fig. 1 an interrupter 7 is inserted in the cable 2 between the machine 1 and a sound transmitter consisting of a diaphragm 5 and a magnet system 6. 90

According to Fig. 2 a rotating change-over switch 4, driven by a motor not shown in the drawings, alternately connects at regular intervals successively one or the other of the two cables 2 and 3 to the machine 1. One end of the magnet winding of the sound transmitter 5, 6 (consisting of a diaphragm 5 and a magnet system 6) is connected to the ends of the cables which are joined together. The other end of the magnet system is earthed as is also the second pole of the alternating current machine 1. 95

In the example shown in Fig. 3 a motor driven interrupter 7 is inserted between the machine 1 and the switch 4 which interrupts the continued alternating current from the machine periodically. The interruption is preferably timed so that a num- 100
105
110

ber of alternate connections take place at 4 in each period.

The insertion of the interrupter between the outer ends of the cables and the transmitter is more preferable for giving signals even if it is more difficult technically since then the signals remain unaltered in the cables while the tone of the transmitter is sub-divided into dashes and spaces. Such an arrangement is shown in Fig. 4. The cable current is alternately conducted, by means of an interrupter 7, driven by an alternating current motor 8, to earth through the transmitter 5 or through a substitute aggregate consisting of a resistance 9 and inductance coil 10. For driving the motor 8 a conductor can be branched from the cable leading to the interrupter.

The different connections possible for the sound transmitter and the possible kinds of signalling which can be employed with an arrangement constructed in accordance with the invention are not intended to be limited to the actual forms shown. For instance the constructive form of the sound transmitter is without importance so far as the essential features of the present invention are concerned.

I claim:

1. In combination with a pilot conductor disposed under water on a predetermined line and carrying alternating currents supplied to it at one end for the purpose of indicating the said line, an electric subma-

rine sound transmitter submerged at and connected to the outer end of the conductor and adapted to be operated by alternating current.

2. In combination with a pilot conductor disposed under water on a predetermined line and carrying alternating currents supplied to it at one end for the purpose of indicating the said line, an electric sound transmitter submerged immediately adjacent to the outer end of the conductor and operated by alternating current, and an interrupter adapted to cause the transmitter to emit predetermined signals.

3. In combination with a pilot conductor disposed under water on a predetermined line and carrying alternating currents supplied to it at one end for the purpose of indicating the said line, an electric sound transmitter submerged at and connected to the outer end of the conductor and adapted to be operated by alternating current, an interrupter for interrupting the alternating currents at certain intervals so as to cause the said transmitter to emit predetermined signals, an electric motor also operated by the said current for driving the said interrupter, both the motor and the interrupter being located at the outer end of said conductor.

In testimony whereof I affix my signature.

WALTER HAHNEMANN.
